Primary Examiner — Eric Goodman*Assistant Examiner* — Alyse Joseph(74) *Attorney, Agent, or Firm* — McAndrews Held & Malloy, Ltd.(57) **CLAIM**

The ornamental design for a display screen or portion thereof with animated graphical user interface, as shown and described.

DESCRIPTION

FIG. 1 is the first image in a sequence for a display screen or portion thereof with animated graphical user interface showing our new design;

FIG. 2 is the second image thereof;

FIG. 3 is the third image thereof;

FIG. 4 is the fourth image thereof; and,

FIG. 5 is the fifth image thereof.

The even length dashed broken lines are for environmental purposes only and form no part of the claimed design.

The uneven length dash-dot broken lines of the display screen represent an unclaimed boundary line and form no part of the claimed design.

The appearance of the transitional image sequentially transitions between the images shown in FIGS. 1-5.

The subject matter in this patent includes a process or period in which an image changes into another image. This process or period forms no part of the claimed design.

The text, "HR," and position of said text, is part of the claimed design.
